(57) CLAIM

The ornamental design for a “charging electronic cigarette case,” as shown and described.

DESCRIPTION

FIG. 1 is a top, front and right side perspective view of a charging electronic cigarette case showing my new design; FIG. 2 is a bottom, front and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a top, front and right side perspective view of the charging electronic cigarette case with a cover thereof being flipped.

The broken lines in drawings are for illustrative purposes only and form no part of the claimed design.
